GOVERNOR FOR INTERNAL COMBUSTION ENGINES

James L. Yarian, Chicago, Ill., assignor to Montgomery Ward & Co., Incorporated, Chicago, Ill., a corporation of Illinois

Application December 18, 1936, Serial No. 116,634

3 Claims. (Cl. 123—108)

The present invention relates to governors for internal combustion engines by which the speed thereof is automatically controlled.

The primary object of the invention is to provide a governor of the character stated designed for engines which are utilized for driving light machinery and, therefore, necessarily light in weight and compact in construction. In adapting the governor to these conditions it is desirable that the same shall be simple, effective and capable of ready assembly in the engine structure. The invention seeks to accomplish this end.

A further object of the invention is to provide a governor the parts of which are so organized and related as to be readily accessible for repair and replacement when required.

Furthermore, the invention contemplates a novel type of governor of such form and construction that its major operative parts are concealed within the engine casing, and thus subject to lubrication by the general lubricating means of the engine, the elements by which the governor is adjusted for varying the degree of control to be exercised by the governor being located at the exterior of the casing, and thus conveniently accessible for manipulation when such is required.

Other objects and advantages will appear as the nature of the improvements is better understood, the invention consisting substantially in the novel construction, combination and arrangement of parts as will be hereinafter fully described, illustrated in the accompanying drawings, and pointed out in the appended claims.

While the form of the invention herein shown and described is believed to be a preferred embodiment thereof, it is to be understood that the same is susceptible to change, modification and variation. The present delineation, therefore, is to be considered from the illustrative standpoint and not as imposing restriction or limitation on the invention.

In the drawings,

Fig. 1 is a side elevation of an internal combustion engine equipped with a governor constructed in accordance with the herein described invention;

Fig. 2 is a vertical sectional view of the engine casing at the point where the cam shaft is located, illustrating certain operative parts of the present governor;

Fig. 3 is a vertical sectional view, as on the line 3—3, Fig. 2;

Fig. 4 is a similar view on the line 4—4, Fig. 2;

Fig. 5 is a side elevation of the shifting means for the throttle-actuating mechanism; and

Fig. 6 is a sectional plan view as on the line 6—6, Fig. 5.

Referring in detail to the accompanying drawings, the numeral 10 designates an internal combustion engine of the air-cooled type, of light power, and light in weight and construction, which is designed for the driving of light machinery. The present invention is not concerned with the engine structure itself, except to the extent that the herein described governor is utilized to control the speed of the engine. There is the usual crank shaft 11, and a cam shaft 12, the cam shaft actuating the usual inlet and exhaust valves 13 and 14, respectively.

The herein described governor is actuated from the cam shaft 12, thus being operated at the lower speed of this shaft as distinguished from the higher speed of the crank shaft 11.

It is understood that the governor is designed to control the position of the throttle valve in the intake of the engine, which throttle valve usually is a pivoted butterfly valve having a rocker arm 15 connected to the shaft of the valve, and projecting at the exterior of the engine casing. This is conventional construction.

The herein described governor includes a sleeve 16 which is slidably mounted upon the cam shaft 12 within the casing 17. The sleeve 16 is in the form of a spool and is provided with a peripheral groove 18 so as to provide heads at the ends of the sleeve.

Adjacent one end of the sleeve 16 is a transversely-arranged supporting head 19, which head 35 has a longitudinal bore 20, and within said bore is fitted a fastening pin 21 which extends through a passage 22 formed in the cam shaft 12. By means of the pin 21 the supporting head 19 is connected to and held upon the shaft 12 for rotation therewith. Hingedly connected to each end of the supporting head 19 is a centrifugally-operating weight 23, each of these weights being of arcuate form so as to fit within the groove 18 of the sleeve 16, but not to contact with the bottom of said groove. Each of the weights 23 has a pair of oppositely-disposed hinge lugs 24 which are spaced apart a sufficient distance to receive therebetween one end of the supporting head 19. A pivotal pin 25 passes through each end of the head 19, each of these pins also passing through the pair of hinge lugs 24 of the weight 23 which is located at the adjacent end of the head 19, and by means of cotter pins 26, or their equivalent, the pivotal pins 25 are held 55

within the hinge lugs 24 so as to hold the lugs on the pins 25. Thus, the weights 23 are free to swing outwardly and inwardly with respect to the supporting head 19 and the sleeve 16. A supporting arm 27 is also carried by each of the 5 weights 23, and a roller 28 is suitably journalled on each of these arms 27. These rollers 28 contact the adjacent end of the slideable sleeve 16, and when the weights are thrown outwardly by centrifugal force, as when the cam shaft 12 has 10 attained a sufficient speed to actuate the throttle valve so as to reduce the speed of the engine, or to check such speed, said rollers 28 will cause the sleeve 16 to slide along the cam shaft 12 15 away from the supporting head 19.

In proximity to the sleeve 16 is located an actuator finger 29, which is relatively wide, said finger being provided with a notch 30 of sufficient width to receive the cam shaft 12, and therefore 20 to permit the actuator finger 29 to straddle said shaft. The actuator finger 29 is fitted in the slotted inner end of a rocker shaft 31 which is journalled in a bearing sleeve 32 carried by an attaching plate 33 which fits over and closes an 25 opening 34 that is formed in the engine casing 17. On the outer end of the rocker shaft 31 is fixedly mounted a bell crank lever 35 provided with a short arm 36 and a long arm 37. The short arm 36 of said bell crank lever 35 is connected to one 30 end of a coil spring 38 the other end of which is attached to a screw 39 which is connected in adjustable relation, by means of nuts 40 and 41, to the engine casing 17. The spring 38 exerts a pull upon the short arm 36 of the bell crank lever 35, and thereby maintains the actuator finger 29 35 in contact with the end of the sleeve 16 which lies adjacent to said finger. Thus, when the sleeve 16 is moved along the cam shaft 12 under the action of the weights 23 when thrown outwardly, the 40 spring 38 resists such movement. On the inward movement of the weights 23, however, as when the speed of the engine has been reduced, the pull of the spring 38 holds the contact finger 29 in engagement with the sleeve 16, and said 45 sleeve is moved in an opposite direction to its movement induced by the outward swinging of the weights 23.

The free end of the long arm 37 of the bell crank lever 35 is pivoted to a connecting rod 42, 50 this rod being adjustably connected to the rocker arm 15 of the throttle valve of the engine. When, therefore, the bell crank lever 35 is operated by the centrifugal action of the weights 23, the long arm 37 is raised so as to close the throttle valve 55 in order to reduce the speed of the engine. When, however, the long arm 37 moves in the reverse direction, as under the pull of the spring 38, as when the speed of the engine has been checked or reduced, the throttle valve is correspondingly 60 opened so that the normal speed of the engine again may be resumed.

In the operation of the herein described governor, it will be understood that the spring 38 is 65 adjusted so that its pull on the bell crank lever 35 will maintain the throttle valve in the proper position for the normal speed of the engine, it being understood that proper adjustment is made so that the engine may idle. When the engine 70 is in operation the weights 23 will not act until the speed of the engine exceeds its normal speed of operation. At such excess speed centrifugal force will throw the weights 23 outwardly, the rollers 28 thereby will move the sleeve 16 along the shaft 12, and the actuator finger 29 there- 75 upon will move under the influence of the sleeve

16 so as to rock the shaft 31 against the pull of the spring 38, so as to shift the throttle valve from its excess opened position to relatively closed position, and thereby reduce the amount of the fuel that is being fed to the engine cylinder. This 5 operation continues until the speed of the engine is reduced, whereupon the weights 23 swing inwardly so as to remove the rollers 28 from pressure against the sleeve 16. With this pressure 10 reduced the spring 38 exerts its pull to force the sleeve 16, through the interposition of the rocker shaft 31, towards the supporting head 19, and thus restores the sleeve 16 to position for action by the outward movement of the weights 23 when the speed of the engine again has exceeded the 15 desired normal limit.

I claim:

1. In an internal combustion engine wherein is embodied a cam shaft arranged within the engine crankcase, and a throttle valve for controlling the feed of fuel to the engine, a rocker shaft mounted in one side of the crankcase and extending transversely with respect to said cam shaft, the inner end of said rocker shaft projecting into the crankcase, connections between the outer end of said rocker shaft and the throttle valve for actuating the latter under predetermined conditions of speed of the cam shaft, an actuator finger mounted on the inner end of the rocker shaft, a sleeve slidably mounted on the cam shaft for operating said actuator finger when the cam shaft has reached a predetermined speed and thereby to actuate said throttle valve to reduce the speed of the engine, a supporting head fixedly connected to the cam shaft adjacent to said slideable sleeve, centrifugally-operating weights hingedly connected to said supporting head and disposed at opposite sides of the cam shaft, contact rollers carried by said weights and cooperating with the slideable sleeve for actuating the latter when the cam shaft has attained said predetermined speed, and means acting in opposition to said centrifugally-operating weights for opening the throttle valve when the speed of the engine has been reduced. 45

2. In an internal combustion engine wherein is embodied a cam shaft arranged within the engine crankcase, and a throttle valve for controlling the feed of fuel to the engine, a rocker shaft 50 transversely mounted in one side of the crankcase and extending transversely with respect to said cam shaft, the inner end of said rocker shaft projecting into the crankcase, connections between the outer end of said rocker shaft and the throttle valve for actuating the latter under predetermined conditions of speed of the cam shaft, an actuator finger mounted on the inner end of the rocker shaft and having a notch therein to receive the cam shaft and to permit the actuator finger to straddle the cam shaft, a sleeve slidably mounted on the cam shaft for operating said actuator finger when the cam shaft has reached a predetermined speed and thereby to 55 actuate said throttle valve to reduce the speed of the engine, a supporting head fixedly connected to the cam shaft adjacent to said slideable sleeve, centrifugally-operating weights hingedly connected to said supporting head and disposed at opposite sides of the cam shaft, contact rollers carried by said weights and cooperating with one 60 end of the slideable sleeve for moving the latter in one direction when the cam shaft has attained said predetermined speed, and means for actuating said rocker shaft to cause the actuator finger to move said sleeve in the opposite direction to 65

70

75

that induced by movement of the centrifugally-operating weights, whereby to open the throttle valve when the speed of the engine has been reduced.

- 5 3. In an internal combustion engine wherein is embodied a cam shaft arranged within the engine crankcase, and a throttle valve for controlling the feed of fuel to the engine, a rocker shaft transversely mounted in one side of the crankcase and 10 extending transversely with respect to said cam shaft, the inner end of said rocker shaft projecting into the crankcase, connections between the outer end of said rocker shaft and the throttle valve for actuating the latter under predetermined 15 conditions of speed of the cam shaft, an actuator finger mounted on the inner end of the rocker shaft and having a notch therein to receive the cam shaft and to permit the actuator finger to straddle the cam shaft, a sleeve slidably mounted on the cam shaft for operating said

actuator finger when the cam shaft has reached a predetermined speed and thereby to actuate said throttle valve to reduce the speed of the engine, a transversely-extending supporting head fixedly connected to the cam shaft adjacent to said slidable sleeve, a centrifugally-operating weight hingedly connected to each end of said supporting head and each disposed at a side of the cam shaft opposite to that at which the other weight is located, a contact roller carried by each of said weights and adapted to engage one end of said slidable sleeve for actuating the latter when said cam shaft has attained said predetermined speed, and means for actuating said rocker shaft to cause the actuator finger to move said sleeve in the opposite direction to that induced by movement of the centrifugally-operating weights, whereby to open the throttle valve when the speed of the engine has been reduced. 15
